UNITED STATES PATENT OFFICE.

LOUIS B. LONDON, OF NEW YORK, N. Y.

DESIGN FOR A BOWL FOR LIGHTING FIXTURES.

Application filed December 27, 1921. Serial No. 525,249. Term of patent 7 years.

To all whom it may concern:

Be it known that I, LOUIS B. LONDON, a citizen of the United States, and a resident of the city of New York, in the county of New York and State of New York, have invented a new, original, and ornamental Design for Bowls for Lighting Fixtures, of which the following is a specification, reference being had to the accompanying drawings, forming part hereof.

The figure of the drawing shows the design of the article.

The figure is a side elevational view of a bowl for lighting fixtures embodying my design.

I claim:

The ornamental design for a bowl for lighting fixtures, as shown.

LOUIS B. LONDON.
